UNITED STATES PATENT OFFICE

163,303

GLOVE BOX

Gerald V. Mazza, New York, N. Y.

Application April 17, 1948, Serial No. 145,788

Term of patent 3½ years

(Cl. D58—12.6)

To all whom it may concern:

Be it known that I, Gerald V. Mazza, a citizen of the United States of America and a resident of the city of New York, in the county of Kings and State of New York, have invented a new, original, and ornamental Design for a Glove Box, of which the following is a specification, reference being had to the accompanying drawing, forming a part thereof:

The single drawing figure is a perspective view of a glove box, showing my new design.

The dominant feature of my design resides in the specific shape and position of the cut-out windows in the box top as shown in the drawing.

I claim:

The ornamental design for a glove box, substantially as shown and described.

GERALD V. MAZZA.
